PORTABLE MACHINE SET-OFF

William M. Lutts, Sr., 4102 Berkshire Ave.,
Louisville, Ky.

Filed Sept. 27, 1957, Ser. No. 686,688

1 Claim. (Cl. 238—10)

This invention relates to portable machine set-offs for removing different types of roadway maintenance machines from the railroad track for the purpose of permitting trains to pass.

In the past there have been set-offs developed to perform this type of operation. The various railroads have given much attention, and have spent large sums of money trying to develop a portable machine set-off that will be practical and safe, and one that can be dismantled, moved and reassembled quickly, so that trains will not be delayed and machines can be used for longer periods of time on the track.

An object of my invention is to provide an improved structure for use in displacing a wheeled vehicle to and from a railroad track and from and into a position alongside the track.

Another object is to provide an improved structure of the above type having a run-off track unit readily alignable with the wheels of a wheeled vehicle prior to movement of that vehicle toward that track unit.

Another object is to provide an improved structure of the above type having means for removably anchoring the same to a railroad track at a selected distance therefrom and without interference with the ties supporting that track.

Other objects and advantages of the invention will become apparent as the description proceeds and when considered in conjunction with the accompanying drawings in which,

Fig. 1 is a plan view showing the structure in assembled position with respect to the railroad track and prior to positioning of the transfer rails upon that track.

Fig. 2 is a view similar to Fig. 1 and showing the transfer rails in position and the vehicle raised in readiness to move along the transfer rails to the run-off track unit.

Fig. 3 is a view similar to Fig. 1 and showing the transfer rails removed to permit passage of a train along the track and with the vehicle resting in set-off position upon the structure.

Fig. 4 is a view similar to Fig. 2 and showing the transfer rails in position and the vehicle in readiness to be transferred to the railroad track.

Fig. 5 is a section taken on line 5—5 of Fig. 2.

Fig. 6 is a section taken on line 6—6 of Fig. 2, and Fig. 7 is a section taken on line 7—7 of Fig. 1.

In accordance with the invention, there is provided a light weight, sturdy, supporting framework having adjustable ground-engaging legs which are adaptable to terrain generally found alongside railroad tracks and which framework can readily be assembled and disassembled rapidly by two men. The framework which is strong enough to support a wide variety of vehicles used for track maintenance, or the like, has a slideable run-off track unit permitting quick alignment with the wheels of the vehicle as when those wheels are raised from the railroad track. In addition, the framework is strongly braced and is adapted to be rigidly anchored to the track at a selected distance therefrom without interference with

2

the ties of the track. A pair of readily removable transfer rails having provision for preventing spreading of the same and for preventing the vehicle from inadvertently rolling off the distal end of the transfer rails, is used to transfer the vehicle from the railroad track to the run-off track unit and to re-transfer the vehicle to the railroad track.

The structure, herein referred to as the portable machine set-off may comprise the following parts and may be used in the following manner. It is assembled and attached to the base of one of the railroad rails 16 as shown in Figure 1. Then a short time before a train is due, the maintenance machine 10 is moved to the location shown in Figure 2, jacked up with the built in jack 13, until the wheels 14 will clear the transfer rails 12, and then rotated a suitable distance from the axis of the railroad track. The transfer rails 12 are then placed in position under maintenance machine 10, and tie bar 15 is attached adjacent the distal ends of those rails thereby to prevent rails 12 from spreading. Maintenance machine 10 is then lowered by means of the jack 13, so that the wheels 14 come to rest on the rails 12. After the jack 13 has been raised enough to clear the railroad rail 16, the maintenance machine 10 is moved, under its own power, on the set-off framework generally shown at 11, and the rails 12 are removed as shown in Figure 3. The train can now pass. As soon as the train has passed, the rails 12 are replaced and tied with the tie bar 15. The machine 10 is then moved over the railroad track, jacked up, rails 12 removed, machine 10 is rotated an appropriate distance and lowered until its wheels 14 come to rest on the railroad rails 16 and 17. After the jack 13 has been raised enough to clear the railroad ties, the machine 10 is moved to the desired position and work is resumed.

Two rail hook assemblies 18 anchor the machine set-off framework 11 and four ground-engaging legs or columns support it. The parallel beams 20 each have a collar 21 at each end which fit around their respective columns 19 and brace the framework in one direction. Tie bars 22 are used to secure quick and accurate positioning of the columns 19 and brace the framework in a second direction. Each run off rail section 23 of the slideable run-off track units has two saddles 24 attached to the under side spaced to register with the beams 20 over which they sit. These saddles 24 prevent the rail sections 23 from moving with respect to the railroad rails 16 in the direction of the rail sections 23, and yet allow the rail sections 23 to be moved in directions parallel to the beams 20. The transfer rail sections 12 each have two insulating members 25 attached to the under side, spaced to register with the railroad rails 16 and 17, so that the machine set-off 11 will not operate railroad signals controlled by track circuits as those transfer rails rest upon the tops of those railroad track rails.

The proximate end of each of the transfer rail sections 12 which mates with an end of run off rail section 23 has a coupling plate 26 attached at the bottom, and a coupling bar 27 attached to each side. The respective transfer rail and run off rail sections 12 and 23 have wheel stops 28 attached to their free ends to prevent machine 10 from going off the rails. Rail sections 12 and 23 are accurately held to the desired spacing or gage by the respective tie bars 15 and 29 which fit into sockets 30 attached to the inner sides of rail sections 12 and 23. The ends 31 of tie bar 15 also provide stops against railroad rail 17, so that, rail sections 12 cannot uncouple improperly from rail sections 23.

Railroad right-of-ways are usually not level and thus the bases 32 of columns 19 are as a rule not all in the same horizontal plane. And in order to have the rail sections 12 and 23 practically level, columns 19 are made

with a number of closely spaced holes 33. The sleeves 21 of beams 20 also have one or more sets of holes 24 which can be made to register with holes 33 by moving the beam 20 up or down. When the beams have been adjusted to get the rail sections 12 and 23 about level, pins 35 are inserted in the nearest set of holes that can be made to register in each of the four columns 19. Pins 35 are attached to beams 20 with chains 36 to prevent loss of the pins.

The rail hook assembly 18 is opened wide enough to allow hook end 37 to be placed over one edge of the railroad rail base and the swivel hook 38 is inserted in one of the holes 39 in plate 40. Then with the V opening in swivel jaw 41 turned so that it will straddle the other edge of the railroad rail base, tubular member 42, which is attached to screw 43, is turned until swivel jaw 41 is forced against the edge of the railroad rail base. Railroad ties are not always uniformly spaced, and because the rail hook assembly 18 is placed between the ties, the position of the swivel hook 38 on the opposite end will vary with tie spacing. Because of this variation in spacing there are a number of holes 39 in each of the plates 40, so that the swivel hook 38 may be inserted in the nearest hole. The rail hook assembly 18 may be varied in overall length by removing bolt 44, and sliding screw 43 in tubular member 42 until hole 45 in the screw registers with a pair of holes 46 in the tubular member. The bolt 44 is then inserted in this set of holes.

Having described my invention, what I claim as new and desire to secure by Letters Patent is:

Means for displacing a wheeled vehicle to and from a railroad track and from and into a position alongside said side track and comprising in combination, a supporting framework including adjustable ground-engaging legs, a plurality of generally horizontal parallel beams supported

by said legs and bracing said framework in a first direction and a plurality of separate bracing members retaining said beams in spaced relation to each other and bracing said framework in a second direction, the axis of said parallel beams being generally parallel to the axis of said railroad track, a run-off track unit including a pair of parallel rails rigidly joined to each other and spaced from each other and slideable along the axis of said beams, means for preventing movement of said run-off track unit transversely of said beams, means for rigidly anchoring said framework to said railroad track at a selected distance therefrom, and a pair of transfer rails parallel to each other and spaced from each other and removably engageable with the tops of the rails of said railroad track and the ends of the rails of said run-off track unit, said transfer rails having means interconnecting the same for preventing spreading thereof during displacement of the vehicle therealong.
